UNITED STATES PATENT OFFICE.

WILLIAM REAVELL, OF IPSWICH, ENGLAND.

AIR-COMPRESSOR.

1,277,752.

Specification of Letters Patent.

Patented Sept. 3, 1918.

Application filed May 7, 1917. Serial No. 166,962.

To all whom it may concern:

Be it known that I, WILLIAM REAVELL, a subject of the King of Great Britain and Ireland, residing at Ipswich, in the county 5 of Suffolk, England, have invented Improvements in Air-Compressors, of which the following is a specification.

This invention has reference to improvements in air compressors of the kind in 10 which two compression cylinders are arranged in line opposite each other and are fitted with pistons reciprocated by a hand lever, an object being to provide a compressor of this kind which shall be capable of 15 compressing air to a very considerable pressure and yet be of simple, strong and efficient construction.

One of our improvements comprises an arrangement wherein the cylinders are carried 20 by a suitable base piece or carrier, which for example may be clamped, or bolted or otherwise secured to a suitable support or which may be in the form of a saddle with hinged jaw or bridle adapted to firmly 25 embrace a bar or tube, and the lever is so formed as to span the cylinders and is pivoted to said base piece or carrier or to the cylinder casting, the limbs of the lever being slotted to receive the ends of a cross 30 head or pin carried by the pistons.

Another improvement comprises a convenient construction and arrangement of two stage compressor with oppositely arranged cylinders and with pistons actuated 35 by a lever in the manner referred to.

To enable the invention to be more clearly understood, constructions of two stage compressors according thereto will now be described with reference to the accompanying 40 illustrative drawings.

Figure 1 is a longitudinal section, of one construction of two stage compressor according to this invention;

Fig. 2 is a transverse section on the line 45 A A Fig. 1; and Figs. 3 and 4 are horizontal sections through the low and high pressure cylinder covers respectively.

Figs. 5 and 6 show in end and side elevation respectively a modified construction.

50 Referring to Figs. 1 to 4, *a* and *b* are the low and high pressure cylinders respectively and are formed of different diameters in the opposite end portions of a casting *c* having intermediate of its cylinders longitudinal slots *d*; the pistons *e* and *f* are of the plunger type formed in one piece having

midway of its length a transverse hole which is bushed to receive a crosshead pin *g* that extends through the slots *d* and is held against endwise movement by collars or washers secured by split pins. The cylinder casting is secured upon a saddle *h* adapted to sit firmly on a support of circular cross section such as the trail of a gun; the saddle may be formed in halves bolted together so as to embrace the gun trail as shown or the saddle proper may have hinged to one side a correspondingly curved jaw, which can be held in its closed position by a pin passing through holes in its free end and the other side of the saddle and which is fitted with a set screw for drawing the saddle down tightly on to its support. In some cases especially in the case of a saddle made in halves and permanently fixed to the gun trail as shown the cylinder casting may be detachably secured to the saddle by interrupted interlocking flanges on the respective parts; as shown, a circular boss *i* having four or other convenient number of radial lugs *i¹* which will pass through corresponding gaps in the inwardly extending flange of a hollow base *h* at the top of the saddle, and, by partially turning the cylinder casting, will engage beneath said flange and firmly secure the casting in its right position, 75

locking being effected by cam shaped lugs or hooks *l* pivoted on the boss of the cylinder casting and adapted to engage studs *m* on the saddle. The actuating lever *n* is pivoted to the lower part of the saddle by studs *o* fixed by screws *p* in the ends of its fork arms and extending into alined holes in bosses *q* at the sides of the saddle, the studs being withdrawable. The bifurcated portion of the lever *n* spans the saddle *h* and the cylinder casting *c* and is formed with guide slots *r* to receive the ends of the crosshead pin *g*; the end portions of the pin are flattened where they engage in the guide slots 80

and the fork arms of the lever are sufficiently splayed that, on being passed over the cylinders, the flattened ends of the pins will enter the guide slots. The upper part of the forked lever is formed as a shouldered socket to receive a bar or tube which may be fixed by a set screw, the axis of the socket lying in the plane containing the center line of the cylinders.

85 The cylinder heads (Figs. 3 and 4) are formed with suction and delivery passages *s* and *t* and valves *u* and *v* the latter prefer- 90

110

ably being interchangeable; the delivery passage *t* of the low pressure end is connected to the suction passage *s* of the high pressure end by a straight tube *w* extending 5 alongside the cylinders exposed to the air, or through the water jacket space where one is provided.

The air inlet and outlet of the compressor may be provided with plugs or caps as shown 10 for exclusion of dirt when the compressor is not in use.

In the construction illustrated in Figs. 5 and 6, and more especially suitable for the larger sizes, the actuating lever comprises 15 two members 1 which are mounted on the end portions of a pin 2 journaled in a bearing 3 formed in one with upwardly extending webs 4 on the cylinder casting, the lower ends of these members being slotted at 5 to engage the flattened end portions of the crosshead pin *g* and the upper ends being formed as sockets into which take the limbs of a U shaped bar or tube 6, which thus holds the members in position on the ful- 25 crum pin 2; mounted to turn on the horizontal middle portion of the U shaped bar or tube is a bar 7 with tubular T pieces at its ends into which can be fitted cross bars so that four men, two to each cross bar, can 30 operate the compressor from opposite sides. As will be understood, this lever arrangement can be easily taken to pieces and packed in a small space.

The operating lever arrangements de- 35 scribed constitute compact and symmetrical driving arrangements in which the pistons are not subjected to side thrust.

Where it is desired to attach compressors to flat surfaces as will usually be the case 40 with the larger sizes, the base piece or carrier may be adapted to be attached thereto by means of claw or other bolts and nuts; or as shown in Figs. 5 and 6 the flat surface may be the face of a hollow boss *k* 45 gapped to receive lugs *i*¹ on a boss *i* on the cylinder casting as already referred to.

Where the cylinder casting has to be mounted so that the cylinder axis is trans- 50 verse of a sloping support such as a gun trail as in Figs. 5 and 6, the boss or base portion *i* of the casting may be correspondingly sloped as shown so that the operating lever will extend vertically.

What I claim is:—

55 1. An air compressor of the kind referred to comprising a casting formed with two cylinders in line in its opposite end portions, connected valveless pistons in said cylinders, a base piece or carrier, interrupted interlocking flanges detachably securing the cyl-

inders thereto, a bifurcated hand lever spanning said cylinders and having slotted arms, a fulcrum on which said lever is detachably mounted, a cross head pin carried by the pistons and engaging at its ends the slots in 65 the lever arms, substantially as described.

2. A two-stage air compressor of the type referred to comprising a casting having cylinders of different diameters formed in its opposite end portions and longitudinal slots 70 in opposite sides of its intermediate portion, a base piece or carrier to which said casting is detachably secured, valveless pistons fitting said cylinders and formed in one piece with a transverse hole midway of its length, 75 a crosshead pin held in said hole and having its ends, which project through said slots, flattened; a bifurcated actuating lever adapted to span the cylinder casting and formed with guide slots in its fork arms, 80 which slots receive and guide the flattened ends of the crosshead pin, and a fulcrum on which said lever is detachably mounted, substantially as described.

3. A two-stage air compressor of the type 85 referred to comprising a casting having cylinders of different diameters formed in its opposite end portions, a base piece or carrier to which said casting is detachably secured, heads to said cylinders, suction and delivery 90 passages and valves in said heads, a tubular connection between the low pressure delivery passage and the high pressure suction passage, longitudinal slots in the opposite sides of the cylinder casting intermediate of the 95 cylinder, valveless pistons fitting said cylinders and formed in one piece with a transverse hole midway of its length, a crosshead pin held in said hole and having its ends, which project through said slots, flattened, 100 a bifurcated actuating lever adapted to span the cylinder casting and formed with guide slots in its fork arms, which slots receive and guide the flattened projecting ends of the crosshead pin, and a fulcrum on which 105 said lever is detachably mounted, substantially as described.

4. A two-stage air compressor according to claim 2 wherein the slotted fork arms of the bifurcated actuating lever are disposed 110 at an angle to each other so that, on being passed over the cylinder casting the flattened ends of the crosshead pin will enter the guide slots, substantially as described.

Signed at Ranelagh Works, Ipswich, this 115 16th day of April, 1917.

WILLIAM REAVELL.
